UNITED STATES PATENT OFFICE.

GEORGE W. FERNSTROM, OF WASHINGTON, DISTRICT OF COLUMBIA.

DISPLAY STAND.

Application filed August 17, 1925. Serial No. 50,774.

To all whom it may concern:

Be it known that I, GEORGE W. FERNSTROM, a citizen of the United States, residing at Washington, in the District of Columbia, have invented new and useful Improvements in Display Stands, of which the following is a specification.

This invention relates to improvements in display stands, an object being to provide a stand which may be made from a single piece of material to provide an attractive device capable of use for displaying various articles, or as a book rest, copy holder or other support.

With the above and other objects in view, the invention further includes the following novel features and details of construction, to be hereinafter more fully described, illustrated in the accompanying drawings and pointed out in the appended claims.

In the drawings:—

Figure 1 is a perspective view of a display stand constructed in accordance with the invention.

Figure 2 is a similar view looking at the rear of the stand.

Figure 3 is a plan view of the blank from which the stand is formed.

Figure 4 is a perspective view partly broken away and showing the stand in partly folded position.

Figure 5 is a detail plan view of the removable shelf.

Referring to the drawings in detail where-in like characters of reference denote corresponding parts, the stand which may be made of any suitable material, such as sheet metal, cardboard or the like, comprises a supporting column 10 which is closed at its top, opposite sides, front and rear, the front including a lower upwardly and rearwardly inclined portion 11 from which extends a vertical portion 12.

Referring to Figure 3 of the drawings, the column 10 comprises a rear wall 13 and side walls 14, the said walls being formed by bending the material along the dotted lines *a*, while the forward edges of the side walls 14 are provided with inclined portions *b*, and portions *c* which are parallel to the lines *a*. At the lower ends of the side walls 14 there are provided base flanges 15 formed by bending the material along the dotted lines *d* so as to provide oppositely located outwardly extending base flanges to stabilize the column 10. The top 16 of the column is

formed by bending the material along the dotted lines *e*, while the upper panel 12 which forms the upper portion of the front wall of the column is provided with side extensions 17 which project beyond the opposite side edges of the column. The panel 17 bears against the edges *c* of the side walls and these edges have extending therefrom brackets or tongues 18 which project through slits 18' provided in the panel 12 and serve to hold the latter in place. Extending from the edges *c* are reinforcing flaps 19 which are folded along the dotted lines *f* inwardly and reinforce the panel 12. The lower panel is bent along the dotted line *g* so that its incline may conform to the inclination of the edges *b* of the side walls 14. This panel is also provided with side wings 20 which extend beyond the opposite sides of the column. The edges *b* of the side walls 14 are provided with tongues or brackets 21 which extend through slits 22 provided in the panel 11 and serve to hold the panel in place. In addition, these brackets may be provided with curved edges 23 so as to securely support a bottle or other object. The top 16 is preferably provided with side flaps 24 which are formed by bending the material along the dotted lines *h*, these flaps being folded within the upper edges of the side walls.

It will be apparent from the foregoing description and accompanying drawings that the construction provides an attractive and strongly constructed stand which may be made of relatively light material of various kinds and when set up will provide a stand or support for the display of different articles of merchandise, while the panels may be utilized for advertising display, or, may have secured thereto hooks or similar devices for the support of different articles. The upper edges of the upper panel 12 may if desired be ornamented as indicated at 100

25, while the brackets 18 may be provided with lugs or extensions 26 to be received within slits 27 formed in a removable shelf 28. This shelf may have its rear edge 28' shaped as illustrated in Figure 5 of the drawings and the panel 12 may be bent along the dotted lines *k* to conform to the shape of the shelf.

If desired, the shelf may be dispensed with and the brackets 18 shaped somewhat 110 similar to the brackets 21 and the side extensions 17 may have extending from their

opposite edges, straps 29. These straps are designed to extend along the rear of the column 10 and may have their ends adjustably connected by any suitable means. For example, the straps 29 may be provided with spaced openings 30 for the passage of a tape or cord 31, or other suitable fastening device. By adjustably connecting the straps 30, the shape of the panel 12 may be controlled so that the side extensions 17 of said panel may be adjustably regulated with respect to the intermediate portion thereof.

10 The invention is susceptible of various changes in its form, proportions and minor 15 details of construction and the right is herein reserved to make such changes as properly fall within the scope of the appended claims.

Having described the invention what is 20 claimed is:—

1. A display stand formed from a single sheet of material and comprising a supporting column having an upwardly and rearwardly inclined face, wings extending laterally from opposite edges of said inclined face and combined article supporting brackets and securing tongues extending from the side walls of the column through the panel.

2. A display stand formed from a single 30 sheet of material and comprising a supporting column having an upwardly and rearwardly inclined face, wings extending laterally from opposite edges of said inclined face and combined article supporting brackets and securing tongues extending from the side walls of the column through the panel and base flanges extending outwardly from the lower edges of the column.

3. A display stand formed from a single 40 sheet of material and comprising a supporting column closed upon its sides, front, rear and top and having an upwardly and rearwardly inclined face, wings extending laterally from opposite edges of said inclined face and combined article supporting brackets and securing tongues extending from the side walls of the column through the panel.

4. A display stand formed from a single 50 sheet of material and comprising a supporting column closed upon its sides, front, rear and top, said front including a lower upwardly and rearwardly inclined panel and an upper vertically disposed panel and com-

bined supporting brackets and securing tongues extending from the side walls of 55 the column through said panels.

5. A display stand formed from a single sheet of material and comprising a supporting column closed upon its sides, front, rear and top, said front including a lower upwardly and rearwardly inclined panel and an upper vertically disposed panel, said panels extending beyond the sides of the column and combined supporting brackets and securing tongues extending from the side walls of the column through said panels.

6. A display stand formed from a single sheet of material and comprising a supporting column closed upon its sides, front, rear 70 and top, said front including a lower upwardly and rearwardly inclined panel and an upper vertically disposed panel, said panels extending beyond the sides of the column and combined supporting brackets 75 and securing tongues extending from the side walls of the column through said panels and means to adjust the extended ends of the upper panel relative to the intermediate portion thereof.

7. A display stand formed from a single sheet of material and comprising a supporting column closed upon its sides, front, rear and top, said front including a lower upwardly and rearwardly inclined panel and an upper vertically disposed panel, said panels extending beyond the sides of the column and combined supporting brackets and securing tongues extending from the side walls of the column through said panels 90 and adjustably connected straps extending from the outer edges of the upper panel.

8. A display stand formed from a single sheet of material and comprising a supporting column closed upon its sides, front, rear 95 and top, said front including a lower upwardly and rearwardly inclined panel and an upper vertically disposed panel and combined supporting brackets and securing tongues extending from the side walls of 100 the column through the panels and a horizontally disposed shelf mounted upon the brackets and engaging the face of the upper panel.

In testimony whereof I affix my signature.

GEORGE W. FERNSTROM.
